UNITED STATES PATENT OFFICE.

WALTER G. WERBECK, DECEASED, LATE OF CHICAGO, ILLINOIS, BY CARL W. HAGEMANN, ADMINISTRATOR, OF CHICAGO, ILLINOIS, ASSIGNOR TO S. S. P. MANUFACTURING CO., OF CHICAGO, ILLINOIS.

FLUID GAUGE.

Application filed March 26, 1921. Serial No. 455,909.

To all whom it may concern:

Be it known that WALTER G. WERBECK, deceased, a citizen of the United States, and a late resident of the city of Chicago, county 5 of Cook, and State of Illinois, has invented certain new and useful Improvements in Fluid Gauges, of which the following is a specification.

My invention relates to fluid gauges of 10 the character employed in measuring the amount of water contained in a boiler or the like, and has for its principal object the provision of an improved construction of this character which will be highly efficient 15 in use.

A further object of my invention is the provision employed whereby the gauge glass can be readily removed without the removal of the valves supporting the same.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1 is a side elevational view, partly in section, of the construction embodied in the 30 invention; and

Fig. 2 is a front elevational view of the same partly in section.

The preferred form of construction, as 35 illustrated in the drawings, comprises a pair of hand valves 5 and 6 which are rigidly fixed to a steam boiler or water column 7, by bolting a flange 8, integrally formed on the inner end of a valve casing 9 and 10, to a flange 11, integrally formed on one end of a 40 nipple 13 and 14, which is threaded into the steam boiler or water column 7. The valve 6 is provided with a laterally extending arm 15 having vertically aligned bores 17 and 17' arranged to receive a glass tube 18. The 45 vertically extending bore 17' being smaller in diameter than the other of said bore 17, is arranged to serve as a seat for one end of the glass tube 18. Opposite the laterally extending arm 15, the valve casing 10 is

provided with another laterally extending 50 arm 19 having a bore 12 in alignment with the bores 17 and 17' and in which a blow-off cock (not shown) may be threaded. The valve 5 is provided with a laterally extending 55 arm 16 having a vertically extending bore 16' in alignment with the bores 17 and 17' and arranged to receive the other end of the glass tube 18. The edge of the bore 16' being beveled to allow the glass tube 18 to be 60 swung clear of the arm 15 when removed. The laterally extending arms 15 and 16 are provided with a housing or packing boxes 20 and 21, each of which are provided with laterally extending slotted ears 22 and 22'. The ears 22 and 22' are arranged to receive 65 a pivotally mounted bolt 23 and 23' having a hexagon nut 24 threaded thereon. The bolts 23 and 23' are pivoted between vertically extending slotted ears 25 and 25' which are rigidly fixed to the valve casings 9 and 70 10. Vertically extending rods 26 are secured to the valve casings 9 and 10 and serve to hold the valves rigid and in alignment. A ring washer 28 formed of rubber 75 or any other suitable material is carried in the packing boxes 20 and 21 and provided with a groove 28' which will expand when the steam or other pressure is applied. The inner lip 29 of the ring washer 28 is forced 80 against the glass tube 18 forming a cushion. The outer portion of the said washer is forced against the inside wall of the packing boxes 20 and 21 preventing the leakage of steam or the like.

In use, when it is desired to renew the 85 glass tube 18 by partly unthreading the nuts 24, which can be turned with the fingers, and then swinging the pivotally mounted bolts 23 and 23' free from the slotted ears 22 and 22', the packing boxes 20 and 21 90 can be easily raised clearing the laterally extending arms 15 and 16. The glass tube 18 is then forced upwardly clearing the bore 17, swung free of the laterally extending arm 15, and is then easily removed.

95 To replace the glass tube 18, by first inserting the said tube through the bores provided in the packing boxes 20 and 21 and by

a reversed operation, the task can be easily accomplished without disturbing or removing any of the other parts of the valve.

While I have illustrated and described the 5 preferred form of construction for carrying my invention into effect, this is capable of variation and modification without departing from the spirit of the invention. I, therefore, do not wish to be limited to the 10 precise details of the construction set forth, but desire to avail myself of such variations and modifications as come within the scope of the appended claims.

Having described my invention, what I 15 claim as new and desire to secure by Letters Patent is:

1. In a fluid gauge, the combination with a pair of oppositely disposed valve casings having centrally aligned bores; a removable transparent tube arranged to engage said bores; movable packing boxes associated with said valve casings; and means pivotally mounted on said valve casings for engagement with said packing boxes for holding said boxes in operative position.

2. In a fluid gauge, the combination with a pair of oppositely disposed valve casings having centrally aligned bores; a transparent tube positioned in said bores, one 30 of said bores being tapered inwardly to permit swinging movement of said tube and the other of said bores being provided with an annular shoulder affording a seat for said tube; packing boxes associated with said casings; and pivotally mounted means associated with said casings for engagement with said packing boxes for holding said boxes in operative position.

3. In a fluid gauge, the combination with 40 a pair of oppositely disposed valve casings having laterally extended portions provided with centrally aligned bores; a gauge tube positioned in said bores; packing boxes mounted for vertical movement on said extended portions and embracing the end portions of said tube; and pivotally mounted means on said casings for holding said boxes in operative position and for affording means for readily permitting movement of 50 said boxes upon being disengaged therefrom to permit removal of said tube.

4. A fluid gauge of the class described comprising a transparent tube; a pair of oppositely disposed valves; laterally extending members on each of said valve casings and having aligned bores formed therein, the inner portion of one of said bores being arranged to serve as a seat for said tube; packing boxes mounted for vertical movement on said valve casings and provided with laterally extended ears; slotted members on said casings; and means pivotally carried by said member for engagement with said ears for holding said packing boxes in operative position.

5. A fluid gauge of the class described comprising a gauge glass; a pair of oppositely disposed valve casings; laterally extending members formed on said casings and provided with vertically extending bores, the inner portion of one of said bores being smaller in diameter than the outer portion thereof to serve as a seat for said gauge glass; slidably mounted packing boxes provided with laterally extending slotted ears; nut carrying bolts pivotally mounted on said casings for engagement with said slotted ears for holding said packing boxes in operative position.

6. In a fluid gauge, the combination with 80 a pair of valve casings, of a slidably mounted packing box associated with each of said casings; laterally extending slotted ears formed on opposite corresponding sides of each of said packing boxes; and nut receiving bolts pivotally mounted on each of said valve casings for engagement with said slotted ears for holding said packing boxes in operative position.

7. In a fluid gauge, the combination with 90 a pair of oppositely disposed valve casings, of a packing box mounted for vertical movement on each of said casings; and pivotally mounted means on each of said casings for engagement with said packing boxes to hold said packing box in operative position.

8. A fluid gauge of the class described comprising a pair of oppositely disposed valve casings; laterally extending portions formed on each of said valve casings and provided with vertically aligned bores; a gauge glass formed of transparent material removably inserted in said bores, one of said bores being tapered to permit swinging movement of said gauge glass; an annular shoulder formed in the other of said bores affording a seat for said gauge glass; a slidably mounted packing box on each of said extending portions and arranged to 100 embrace the adjacent end portion of said gauge glass; oppositely disposed slotted ears formed on said packing boxes; and lock-bolts pivotally mounted on said valve casings for engagement with said slotted ears 110 for locking said packing boxes in operative position.

9. In a fluid gauge, the combination with 120 a pair of oppositely disposed valve casings, of a removable gauge glass supported by said casings; and pivotally mounted means on said valve casings affording means for readily mounting and removing said gauge glass.

10. A fluid gauge comprising vertically 125 aligned valve casings having flanges formed thereon affording means of attachment to a fluid container or the like, there being vertically aligned bores formed in said casings; a gauge glass having its ends engag- 130

ing said bores; movable packing boxes having lateral slotted ears carried by said casings and through which the ends of said gauge glass pass, and members swingingly carried by said casings adapted to engage the slots formed in said ears for holding said packing boxes in position to prevent removal of said gauge glass.

In testimony whereof I have signed my

name to this specification in the presence of two subscribing witnesses.
